UNITED STATES PATENT OFFICE.

GUSTAVE LEVE, OF NEW YORK, N. Y.

BERTH FOR PASSENGER-STEAMERS.

SPECIFICATION forming part of Letters Patent No. 249,376, dated November 8, 1881.

Application filed March 28, 1881. (No model.)

To all whom it may concern:

Be it known that I, GUSTAVE LEVE, of the city, county, and State of New York, have invented certain new and useful Improvements 5 in Berths for Passenger-Steamers; and I do hereby declare that the following is a full, clear, and exact description of the same.

My invention is specially intended for use on passenger-steamers for coast and inland 10 navigation, on which the number of passengers carried is occasionally very much in excess of the ordinary amount, necessitating a corresponding increase in sleeping accommodation.

I propose, without in any way increasing the 15 number of state-rooms or interfering with the plan or arrangement of the vessel, to provide means whereby on special occasions almost double the ordinary amount of sleeping accommodation can be afforded.

20 My invention may be briefly described as follows: In or on the partitions dividing off the rows of state-rooms from the central saloon, as is usual in passenger-steamers, and in the spaces between such state-room doors, I 25 form cupboards, the front of which will appear during the day, or when the extra accommodation is not required, as part of the side of the saloon. In these, which may project out into the saloon or be recessed into the state- 30 rooms, and which can be of any width desired, are stowed berth frames or mattresses and bedding sufficient for one or two berths, as the case may be, the depth of the cupboard being regulated accordingly. On the special occasions 35 above mentioned, when more sleeping accommodation is required, all that is needed is to undo the fastenings securing the cupboard-front to the saloon-partition and draw it out at right angles thereto, suitable rollers, casters, 40 or their equivalent being provided for it to move upon. The distance these move out is regulated and their vertical position maintained by bars, links, or rods pivoted to the cupboard front and partition and hinged centrally, so as to fold up and down, their length, 45 when extended, corresponding with that of an ordinary berth. When these are drawn out the cupboard-front forms the end of the berth, and all that is then needed is to place in position the bed frames or mattresses, these being 50 carried on suitable pins or supports secured

on the inside of the cupboard. For full comprehension, however, of my invention reference must be had to the annexed drawings, showing one way in which my invention may be embodied, and in which—

Figure 1 is a perspective view of part of a steamboat-saloon, showing one cupboard-front drawn out and the berth made up, and another as it appears during the day; and Fig. 2 is a 60 longitudinal section through the berth.

Similar letters of reference indicate like parts.

A is the cupboard-front, which is usually mounted on rollers, casters, or other devices, 65 so as to allow of its moving freely on the floor, paneled or otherwise ornamented to correspond with the decoration of the saloon, and in this case secured by hooks or catches of any kind, or by bolts, to standards or styles B, projecting 70 from the saloon-partition C, and wide enough to give sufficient depth to the cupboard to hold therein the berth frames and bedding, which will be stowed on end. The cupboard-front is secured to these standards B B by rods or bars 75 D D', pivoted to each and hinged, as shown, in the middle, so as to fold respectively down and up.

E show any suitable hooks, pins, or projections, arranged on the inside faces of C and 80 A, for the purpose of carrying the berth-frames, which may also be of any desired make. Curtains may, as shown, be suspended from the upper bars or rods, D D', thus insuring complete privacy.

85 Although in the above is described one way which will be found very useful of putting my invention into practical operation, it must be understood, as I have before mentioned, that I do not confine myself to the precise details 90 therein set forth, and that with varying requirements these may be modified without in any way interfering with the invention. The cupboard-fronts may have returns, which may work in connection with the standards B or 95 be used in their stead; or the cupboards for holding the berths and bedding may be recessed into the state-rooms and the saloon-partition then appear flush, or they may be formed in or on transverse partitions, as may be required. Again, these adjustable berths may 100 be substituted for the ordinary stationary cots

in the state-rooms themselves, thus allowing the latter to be used in the day-time as sitting-rooms; and, further, although the invention is especially applicable to passenger-steamboats, 5 it will be found of great utility in small craft, such as yachts, and may therein replace standing berths, the cupboards holding the bed-frames, &c., being formed in the side of the vessel. It may also be utilized in the steerage 10 of passenger-steamers and in transports.

What I claim, and desire to secure by Letters Patent, is as follows:

1. In any vessel carrying passengers, compartments or cupboards for holding berth frames, bedding, &c., in part constituted of a portion of the fixed partitions or walls of the 15

vessel, the fronts of said cupboards being adapted to be drawn out from said fixed portions, and when in that position serving as the end of the berth-frames, the other end being 20 supported on the inside of the fixed cupboard, all substantially as described.

2. In any vessel, cupboards or recesses formed in or on the fixed partitions or sides of the vessel, and having their fronts attached 25 thereto by pivoted bars or links D, hinged centrally of the extended berth, as and for the purposes set forth.

GUSTAVE LEVE.
